[57] CLAIM

The ornamental design for a hand-held personal security device for emitting a chemical spray as well as providing an audible alarm and a light, as shown and described.

DESCRIPTION

FIG. 1 is a top, front and side perspective view of a hand-held personal security device for emitting a chemical spray as well as providing an audible alarm and a light according to the invention;

FIG. 2 is a right side view in elevation thereof;

FIG. 3 is a left side view in elevation thereof;

FIG. 4 is a front view in elevation thereof;

FIG. 5 is a top plan view in elevation thereof;

FIG. 6 is a rear elevational view thereof; and,

FIG. 7 is a bottom plan view thereof.
